(57) **CLAIM**

The ornamental design for a handle with gimbal for camera or the like, as shown and described.

DESCRIPTION

FIG. 1 is a top front perspective view of a handle with gimbal for camera or the like showing the claimed design; FIG. 2 is a bottom rear perspective view thereof; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the handle and gimbal that form no part of the claimed design.

The shade lines in the figures show contour and not surface ornamentation.
